COMBINED BOBBY PIN AND PERFUME
PELLET HOLDER

Joan Weiss, 325 E. 77th St., New York, N.Y.

Filed Feb. 28, 1964, Ser. No. 78,827

Term of patent 14 years

(Cl. D86—10)

I claim:

The ornamental design for a combined bobby pin and perfume pellet holder, substantially as shown.
